UNITED STATES PATENT OFFICE.

WALTER O. HALL, OF FRANKLIN, MASSACHUSETTS, ASSIGNOR, BY DIRECT AND MESNE ASSIGNMENTS, TO AMERICAN TYPE FOUNDERS COMPANY, OF JERSEY CITY, NEW JERSEY, A CORPORATION OF NEW JERSEY.

TRANSFER MECHANISM.

Application filed February 26, 1923. Serial No. 621,438.

The present invention relates to sheet transfer mechanism for printing presses of the oscillating type, more commonly called "job presses", and is particularly adapted 5 for use with presses of this type which have an oscillating platen and a stationary bed, such as the Golding press.

The problem of producing a practical and efficient automatic sheet feed and delivery for printing presses of the oscillating-platen, crank driven type is of great complexity and difficulty as compared with the problem of producing an automatic device of this kind for presses of the stationary-15 platen-oscillating-bed type and presses with oscillating platen and bed. Several practical automatic feed and delivery devices have been produced for presses of the latter types, but so far as I am aware no practical 20 mechanism has heretofore been produced for presses of the stationary-bed crank-driven and oscillating-platen-type. The difficulty is due to the movements of the platen on which the sheets are to be deposited 25 and from which the printed sheets are to be taken, and the consequent necessity of so timing the movements of the feeding devices and the delivery devices relative to each other and relative to the oscillation of 30 the platen that they will deposit the sheets on the platen and take the printed sheets therefrom smoothly and without interference with each other or with the platen.

The object of the present invention is to 35 overcome the difficulty referred to above and produce a practical and efficient sheet feed and delivery for presses of the oscillating-platen, crank-driven type; and to this end the invention resides in mechanism which 40 will hereinafter be particularly described and the novel features whereof will be pointed out in the claims.

Although the present invention has been 45 designed with particular reference to presses of the oscillating-platen, crank-driven type, there are certain features of the invention that are applicable to presses of other types, as will be apparent hereinafter.

Generally stated, the sheet feeding and 50 delivery mechanism of the present invention comprises two or more pairs of horizontally aligned sheet feeding fingers mounted to oscillate bodily in vertical planes intersecting the platen and moving in paths extend-

ing from elevated points in front of the press 55 to points adjacent the lower edge of the platen, and a similar set of delivery fingers mounted to oscillate in a path, below the path of the feeding fingers, extending from points in front of the press to points on the 60 face of the platen adjacent the tail edge of the sheet thereon; combined with automatic means for closing the feeding fingers on a sheet, presented thereto by a suitable sheet feeding device, and for opening said fingers 65 when they approach the limit of their movement towards the platen, to deposit the sheet thereon; and automatic devices for closing the delivery fingers on the tail edge of a sheet carried by the platen, and opening said 70 fingers to release the sheet when the fingers approach the opposite limit of their movement. The means for oscillating the feeding fingers preferably includes crank and lever mechanism operating to slow down 75 the movement of said fingers as they approach and recede from the terminal points, so as to allow sufficient time for the platen to open and clear said fingers as they cross 80 the edge of the platen, and so as to permit the delivery fingers to abstract the printed sheet from the platen before the feeding fingers deposit the blank sheet thereon. The means for oscillating the delivery fingers 85 also comprises crank and lever mechanism and preferably said mechanism includes two separate gear trains from the operating shaft of the press so designed as to impart to said fingers a resultant movement which is accelerated while said fingers are moving 90 to and fro over the platen, to cause said fingers to move quickly across the platen, grasp the sheet thereon, and move quickly back out of the way of the feeding fingers, which are simultaneously moving over the 95 platen but with a relatively low velocity. In this manner the feeding and delivery devices are projected and retracted across the face of the platen in such timed relation to the oscillation thereof and with such 100 relative velocities that the sheets are deposited thereon and abstracted therefrom smoothly and without interference.

Referring to the accompanying drawings for a particular description of mechanism 105 embodying the present invention:

Fig. 1 is a side view of sheet feeding and delivery mechanism constructed in accord-

ance with the invention and applied to a Golding press;

Fig. 2 is a front elevation, looking towards the right of Fig. 1;

Fig. 3 is a plan view looking down on Fig. 1 of the sheet feeding and delivery carriages and their associated operating mechanism;

Fig. 4 is a sectional plan view taken on line 4—4 of Fig. 1;

Fig. 5 is a detail side view of the means for mounting and operating the sheet gripping fingers;

Fig. 6 is a detail view illustrating the position of parts when the delivery gripper fingers are in open position;

Fig. 7 is a detail view of a shaft on which the upper gripper fingers are adapted to be mounted;

Fig. 8 is a detail view of a driving means for the delivery carriage;

Fig. 9 is a detail view illustrating the adjustable mounting of the sheet-gripping fingers; and

Fig. 10 is a detail view showing clamping devices between the auxiliary frame and frame of the press.

Referring to the drawings, Fig. 1 shows only sufficient parts of a press of the Golding type to illustrate the application of the present invention thereto. A designates the frame; B, the stationary form bed; and C, the oscillating platen. The platen, pivoted to the frame at D, is operated by well known mechanism shown partly in dotted lines in Fig. 1. Said mechanism is operated from a power or driving shaft 1 carrying a pinion 2 which meshes with a large gear 3 on a main operating shaft 4; and comprises a crank 5 on shaft 4, a link 6 connecting said crank to radius bars 7; a toggle 8, 9 connecting the radius bars to the platen, and a pair of draw bars 10 connecting the toggle with frame A and extending across the ends of the platen.

The sheet feeding and delivery mechanism is adapted to be mounted on an auxiliary frame attached to the press frame A and extending across and spaced from the front of the press. The auxiliary frame is shown in side elevation in Fig. 1 and in front elevation in Fig. 2. It is of rectangular form and comprises vertical side bars 11 connected at their upper ends by a horizontal bar 12 and braced at their lower ends by a rod 13. Said auxiliary frame is preferably pivotally mounted at the side on the press frame, so that it may be swung horizontally, with the sheet feeding and delivery mechanism carried thereby, ninety degrees or more from operative position, to permit access to the press. For this purpose one of the side bars 11 has a pair of parallel arms 14 extending towards the press and terminating in bifurcations 14^a which are

adapted to straddle lugs 15^a formed on the ends of a pair of brackets 15 secured to and projecting from the sides of frame A. The bifurcated ends of arms 14 have vertical perforations which register with perforations in the lugs of brackets 15, and pins 14^b passing through these perforations pivotally connect the frames. The other side bar 11 has a pair of parallel arms 14 which extend towards the frame 15 and terminate in right angular portions 14^c which have open slots to receive threaded bolts 14^d hinged to the frame 15. Bolts 14^d are provided with knurled pieces 14^e. When the pieces 14^e are unscrewed and bolts 14^d swing out of the slots in 14^c and the operating links between the driving shaft of the press and the sheet conveying mechanism are disconnected, the auxiliary frame and said mechanism may be swung about a vertical axis to the side entirely out of the way of the bed and platen.

The mechanism for feeding sheets to the platen comprises two or more pairs of sheet gripping fingers supported from a pair of arms 16, which are keyed to the ends of a horizontal shaft 17 journaled in the side bars 11. The arms 16 are oscillated by mechanism comprising a link 18 connected at one end to one of said arms and at its other to a crank 19 secured to the large gear wheel 3. Each pair of sheet gripping fingers, as more clearly shown on Figures 5, 6 and 10, consists of an upper movable finger 20 and a lower relatively stationary finger 21. The upper fingers 20 are secured to split collars 20^a which are adjustably mounted on a shaft 22, which extends transversely between the arms 16 and is rotatably supported in the ends of said arms. The lower relatively stationary fingers 21 are attached to dove-tail blocks 21^a which are frictionally held in a dove-tail groove formed on the under side of a rod 23, which acts both as a support for said fingers and a tie rod for arms 16. The fingers are thus adjustable longitudinally of the shaft and rod to suit sheets of different widths.

Secured to shaft 22 outside of the arm 16 is an arm 24 carrying a roller 25 at its free end. Inside of the arm 16 the shaft 22 carries a collar 26 in which is formed a notch 27. A spring 28, secured at one end to arm 16 and at its other end to shaft 22, tends to rotate said shaft in a direction to close the fingers 20 on the relatively stationary fingers 21. The fingers 20 are moved to open position, or cocked, by roller 25 coming in contact with draw bar 10, as the feeding mechanism approaches the limit of its movement towards the platen. Said fingers are held open during the return movement of the feeding mechanism, and until the latter approaches the limits of its movement toward a pile of sheets, by means of a pawl 29

engaging the notch 27 in collar 26. Pawl 29 is attached to or integrally formed with an arm 30, which is pivoted on the tie rod 23 inside of the arm 16 and urged by a suitable spring in a direction to engage said pawl with the notch. An arm 30 carries a roller 31 which engages a cam 32 when the sheet feeding mechanism approaches the limit of its movement towards the sheet pile. 5 As said roller travels along the cam, arm 30 is rotated in a direction to raise the pawl out of the notch, permitting spring 28 to rotate shaft 22 and close, or uncock, fingers 20. As 10 said fingers close, they grip a sheet against the relatively stationary fingers 21, said sheet having been presented to grippers 20 and 15 21 by any suitable automatic sheet feeding device.

The mechanism for taking the printed 20 sheets from the platen and delivering same to a suitable conveyor comprises sheet gripping fingers supported by a carriage 33 which reciprocates on a fixed track 34 rigidly attached at one end to a side of the auxiliary frame. Like the feed grippers, the 25 delivery grippers consist of two or more pairs of fingers, the members of which are mounted respectively on a shaft and a rod extending transversely between the sides of the carriage. Each pair of these fingers 30 consists of a relatively stationary lower finger 35 adjustably secured to the underside of a tie rod 36, and an upper movable finger 37 adjustably mounted on the upper side of 35 a shaft 37^a. The fingers are adjustable longitudinally of the shaft and rod to conform with differences in sheet widths.

An arm 38 on shaft 37^a has a notched boss, formed with a notch 38^a which is adapted 40 to be engaged by a pawl 39^a secured to an arm 39 which is pivoted on tie rod 36; and the shaft 37^a is urged by a suitable spring 37^b in a direction to close fingers 37 on the relatively stationary fingers 35, the construction being similar to the construction of the controlling means for the feed fingers above described.

When carriage 33 approaches the limit of its movement away from the platen, a roller 38^b on arm 38 contacts a cam 40 (Fig. 2), which is adjustably mounted on a bracket 40^a projecting inwardly from a side bar 11. This causes rotation of shaft 37^a and consequent opening, or cocking, of fingers 39, and 55 causes release of the sheet. Fingers 39 are held open, or cocked, during the return movement of the carriage, and until the latter approaches the limit of its movement towards the platen, by the pawl 39^a on arm 39 engaging the notch in the boss of arm 38. As the carriage approaches the limit of its movement towards the platen the tail edge 60 of the sheet thereon enters between the gripping fingers and the roller 39^b on arm 39 65 contacts a projection on the platen, thus

moving the pawl out of the notch 38^a and permitting shaft 37^a to uncock fingers 39, and rotate them in sheet clamping relation to the relatively stationary fingers 35.

The carriage 33 is operated by mechanism now to be described. Journaled on shaft 17, inside the arms 16, are a pair of spaced toothed segments 41 which are rigidly connected together by a bar 42. One of the segments 41 is connected to one end of a link 43, the other end of which is bifurcated to straddle shaft 4. A cap 44 attached to the ends of the bifurcated portions of link 43 carries a roller 45 which operates in a cam track 46 formed on the inner face of a disc 47 keyed on shaft 4. A sleeve 48 on shaft 17 extends completely between the segments 41 and formed integrally with said sleeve are two arms 49 which extend upwardly adjacent the segments 41 and have pivoted at 85 their upper ends a pair of toothed segments 50 which mesh with the segments 41. Secured to segments 50 are upwardly extending arms 51 on the free ends of which are pivoted swivel blocks 52. Blocks 52 are 90 bored through to receive tubular extensions on carriage 33, being adjustably secured to the blocks by set screws 53. Formed integrally with sleeve 48 at one end thereof, is a depending arm 54 which is pivoted to 95 one end of a link 55, the other end of said link being connected to a crank 56 on the shaft 4.

In Fig. 1 the platen is shown in open position with the sheet feeding devices moving 100 thereover towards their sheet depositing position with a sheet S, while the sheet delivery devices are at the limit of their movement towards the platen with the gripping fingers thereof closed on the tail edge of 105 a printed sheet. The shaft 4 is moving counterclockwise and the crank 19 is pulling the link 18 and moving the arms 16 downwardly, while the crank 56 and the cam 46 are on the point of moving link 55 to the 110 right and link 43 to the left, as viewed in Fig. 1. As shaft 4 continues to rotate from the position shown in Fig. 1, the cam track 46 will move the link 43 to the left with a relatively quick movement while the crank 115 56 will operate to move link 55 to the right. Hence segments 41 will rotate in a clockwise direction while arms 49 will rotate in a counterclockwise direction. Segments 50 and the arms 51 rigid therewith will thus be 120 rotated counterclockwise bodily about the axis of shaft 17 and also in the same direction about their pivotal connections with arms 49, the bodily movement of said segments being derived from the rotation of 125 arms 49 by the link 55 and crank 56 and the pivotal movements of said segments on said arms 49 being derived from the rotation of segment 41 and also from the bodily movement of segment 50 on segment 41. Hence 130

- the arms 51 have a resultant movement which is produced by the two separate cam and crank connections, and as will be obvious by an inspection of the construction and relative position of the parts shown by Fig. 1, the motion of arms 51 is greatly accelerated during the movements of the delivery fingers over the platen face. Hence the delivery fingers will move down quickly over the platen to the position shown in Fig. 1 seize the sheet thereon, and move same with equal quickness out of the way of the sheet which the feed fingers are on the point of depositing.
- 15 While the delivery fingers are thus moving over the platen to seize the printed sheet and take same to a suitable point of delivery, the crank 19 is moving the arms 16 with the feed fingers carried thereby from points adjacent the pile P of sheets, down over the platen to their sheet depositing position. When arms 16 approach the limit of their downward movement, the roller 25 on arm 24 makes contact with draw bar 10, thus rotating fingers 20 and releasing the sheet, which falls on the platen, the progress of said sheet being stopped by register fingers 57 which are adjustably attached in any known manner to the lower edge of said platen. The feed fingers have a slightly further downward movement after depositing the sheet which permits them to clear the head of the sheet on their return movement, said fingers during this further movement operating to hold said sheet down on the platen.
- As the delivery mechanism approaches the limit of its movement away from the platen the roller 38^b on arm 38 makes contact with the cam 40, rotating fingers 37 and releasing the sheet held thereby. Any suitable conveying means may be employed for receiving the sheets from the delivery fingers and conveying same to a desired point. Fingers 37 are held in open position by the pawl 39^a on arm 39 engaging the notch 38^a in the boss of the arm 38 and are held open until the roller 39^b on arm 39 makes contact with a projection on the platen outside of the sheet after the fingers have received between them the tail edge of the printed sheet. It will be observed that the delivery mechanism has a substantial dwell at the limit of its movement away from the platen, due to the fact that the cam track 46 is substantially concentric with shaft 4 and the crank 56 is passing over its dead center while the mechanism occupies this position. This gives ample time for the sheet to fall from said delivery fingers and makes it possible to produce the quick movements of said fingers over the platen. It will also be observed that due to the relative positions of the axes of shafts 17 and 4, the crank 19 will give a relatively slow movement to the arms 16 and the feed mechanism carried thereby while said mechanism is approaching the platen and a fast movement away from the platen. Hence ample time will be allowed for the platen to open and clear the feeding fingers as they cross the edge thereof and for the delivery fingers to withdraw the printed sheet from the platen before the feeding mechanism deposits a sheet thereon.
- As the sheets operated on vary in width, it is necessary to adjust for these variations. Therefore the feeding fingers are mounted so that they may be clamped or secured at different points on the shaft 22 and rod 23, while the delivery fingers are adjustable in a similar manner on the shaft 37^a and rod 36, as shown in Figure 10, and the register Fingers 57 are attachable at different points along the edge of the platen. By these means the mechanism is adjustable for any width sheet within the platen range. For adjusting to suit different lengths of sheets the carriage 33 is moved relatively to the swivel blocks 52 and clamped by the set screws 53 or other suitable clamping means in proper position for the particular length of sheet operated on.
- Although an embodiment of the invention has been described in detail, it is not limited to the form shown but includes modifications and changes within the scope of the appended claims.
- Having thus described the invention what is claimed as new and desired to be secured by Letters Patent is:
1. In combination with a printing press of the oscillating type, sheet feeding mechanism comprising a plurality of pairs of sheet gripping fingers mounted for reciprocation in planes intersecting the platen, means actuated by the operating shaft of the press for reciprocating said fingers from points adjacent a pile of sheets to points adjacent the lower edge of the platen when the latter is in substantially open position, and returning said fingers before the platen closes, and automatic means for opening said gripper fingers when they approach the limit of their movement towards the platen and for closing said fingers when they approach the opposite limit of their movement.
  2. In combination with a printing press of the oscillating platen type, sheet feeding mechanism comprising sheet gripping fingers mounted for bodily movement in a curved path extending from a point adjacent the lower edge of the platen, when the latter is open, to points adjacent a pile of sheets, means for so moving said fingers in timed relation to each oscillation of said platen and before the platen closes, means for opening said fingers to deposit a sheet on the platen when said fingers approach the limit of their movement towards the platen, means for holding said fingers open, and means for

- releasing said holding means to permit said fingers to close on a sheet when said fingers approach the limit of their movement towards the sheet pile.
5. In combination with a printing press of the oscillating platen type, sheet feeding mechanism comprising an arm pivoted on a horizontal axis in front of the press, means for oscillating said arm in timed relation to the oscillation of the platen through a complete cycle before the platen closes, two or more pairs of gripper fingers supported from the upper end of said arm and movable thereby in curved paths extending from points adjacent the lower edge of the platen when the latter is open, to points adjacent a pile of sheets, means for opening said fingers to deposit a sheet on the platen when said fingers approach the limit of their movement towards said platen, a detent holding said fingers open, and means for releasing said detent to permit said fingers to close on a sheet when said fingers approach the opposite limit of their movement.
25. 4. In combination with a printing press of the oscillating platen type, sheet feeding mechanism comprising an arm pivoted for movement about a horizontal axis in front of the press and in a vertical plane at the side of the platen, means for oscillating said arm in timed relation to the oscillation of the platen through a complete cycle before the platen closes, two or more pairs of horizontally aligned gripper fingers supported from the upper end of said arm and movable thereby in curved paths extending from points adjacent the lower edge of the platen, when the latter is open, to points adjacent a pile of sheets, means for opening said fingers to deposit a sheet on the platen when said fingers approach the limit of their movement towards said platen, means holding said fingers open, and means for releasing said holding means to permit said fingers to close on a sheet when said fingers are near the opposite limit of their movement.
5. In combination with a printing press of the oscillating platen type, sheet feeding mechanism comprising an arm pivoted in front of the press and positioned to move in a vertical plane at the side of the platen, means for oscillating said arm in timed relation to the oscillation of said platen, a transverse gripper shaft journaled at the free end of said arm, a rod secured to said arm adjacent and parallel to said gripper shaft, upper and lower sheet gripping fingers fixed to said shaft and rod respectively, means for rotating said gripper shaft to open said fingers when said arm approaches the limit of its movement towards the press, a detent holding said shaft, and means for releasing said detent to permit said fingers to close when said arm is near the opposite limit of its movement.
6. In combination with a printing press of the oscillating platen type, sheet feeding mechanism comprising a transverse shaft journaled in front of the press, a pair of arms keyed on said shaft and positioned to operate in vertical planes at the sides of the platen, means for oscillating said arms in timed relation to the oscillations of said platen, a gripper shaft journaled in the free ends of said arms, a tie rod secured to said arms adjacent and parallel to said gripper shaft, upper and lower sheet gripping fingers fixed to said shaft and rod respectively, said shaft being biased to close said fingers, means for rotating said gripper shaft to open said fingers when said arms approach the limit of their movement towards the press, a detent holding said shaft, and means for releasing said detent to permit said fingers to close when said arms approach the opposite limit of their movement.
7. In combination with a printing press of the oscillating platen type, sheet feeding mechanism comprising a pair of arms pivoted in front of the press and positioned to operate in vertical planes at the sides of the platen, means for oscillating said arms in timed relation to the oscillation of said platen, a gripper shaft journaled in the free ends of said arms, a rod secured to said arms adjacent and parallel to said gripper shaft, upper and lower sheet gripping fingers fixed to said shaft and rod, said shaft being biased to close said fingers, means for rotating said gripper shaft to open said fingers when said arms approach the limit of their movement towards the press, a detent holding said gripper shaft, and means for releasing said detent when said arms approach the opposite limit of their movement.
8. In combination with a printing press of the oscillating platen type, sheet feeding mechanism comprising a pair of arms pivoted in front of the platen and positioned to operate in vertical planes at the sides thereof, means for oscillating said arms in timed relation to the oscillation of said platen, gripper fingers supported from the upper ends of said arms and movable thereby in a curved path extending from points adjacent the lower edge of the platen, when the latter is open, to points adjacent a pile of sheets, means for opening said fingers to deposit a sheet on the platen when said fingers approach the limit of their movement towards said platen, means holding said fingers open, and means for releasing said holding means to permit said fingers to close on a sheet when said fingers approach the opposite limit of their movement.
9. In combination with a printing press of the oscillating platen type, sheet feeding mechanism comprising a transverse shaft journaled in front of the press, a pair of arms fixed to said shaft and positioned to

move in vertical planes at the sides of the platen, sheet gripping devices supported from the upper ends of said arms and movable thereby in a curved path from points adjacent the lower edge of the platen when the latter is open to points adjacent a pile of sheets, automatic means for operating said gripping devices to cause them to take a sheet from said pile and deposit same on said platen, a crank on the operating shaft of the press and a link connecting said crank to one of said arms.

10. In combination with a printing press of the oscillating platen type, sheet feeding mechanism comprising a transverse shaft journaled in front of the press, a pair of arms fixed to said shaft and positioned to move in vertical planes at the sides of the platen, a gripper shaft journaled at the free ends of said arms, a tie rod secured to said arms adjacent and parallel to said gripper shaft, upper and lower sheet gripping fingers fixed to said shaft and rod respectively, said shaft being biased to close said fingers, an arm on said shaft adapted to contact the draw bar of the press to rotate said shaft and open said fingers, a detent holding said shaft, a relatively fixed cam to release said detent when said arms approach the limit of their movement away from the press, a crank on the operating shaft of the press, and a link connecting said crank to one of said arms.

11. In combination with a printing press of the oscillating platen type, sheet feeding mechanism comprising an arm pivoted in front of the press and positioned to oscillate in a vertical plane at the side of the platen, sheet gripping devices carried by said arm and bodily movable thereby in a curved path from points adjacent the lower edge of the platen, when the latter is open, to points adjacent a pile of sheets, automatic means for operating said gripping devices to cause them to take a sheet from said pile and deposit same on said platen, a crank on the operating shaft of the press, and a link connecting said crank to said arm.

12. In combination with a printing press of the oscillating platen type, sheet feeding mechanism comprising a plurality of pairs of resilient sheet gripping fingers mounted for movement in vertical planes intersecting the platen, means actuated by the operating shaft of the press for moving said fingers in curved paths extending from points adjacent the lower edge of the platen when the latter is in fully open position to elevated points in front of the platen, means for opening said fingers shortly before they reach the limit of their movement towards the platen to deposit a sheet thereon, adjustable sheet registering fingers at the lower edge of the platen to stop the progress of the

sheet, said gripping fingers operating during their final movement towards the platen to hold said sheet thereon, and means for closing said fingers on a sheet as they approach the opposite limit of their movement.

13. In combination with a printing press of the oscillating platen type, sheet feeding mechanism comprising a plurality of pairs of horizontally aligned sheet gripping fingers mounted for movement in vertical planes intersecting the platen, means operated in timed relation to the oscillation of the platen for moving said fingers in curved paths extending from points adjacent the lower edge of the platen when the latter is fully opened to points adjacent a pile of sheets, and automatic means for actuating said gripping fingers.

14. In a sheet feeding mechanism for printing presses of the oscillating platen type, sheet feeding mechanism comprising a plurality of pairs of sheet gripping fingers mounted for movement in vertical planes intersecting the platen, means actuated by the operating shaft of the press for moving said fingers from points adjacent the lower edge of the platen, when the latter is fully open, to points adjacent a pile of sheets, and automatic means for opening said gripper fingers when they approach the limit of their movement toward the platen and for closing said fingers when they approach the opposite limit of their movement.

15. In combination with a printing press of the oscillating type, sheet feeding mechanism comprising two or more pairs of horizontally aligned feeding fingers, said fingers mounted to move in vertical planes intersecting the platen, means for reciprocating said fingers bodily in timed relation to the oscillation of the press in circular arc paths towards and from the face of the platen and completing this cycle before the platen closes, the path of said feeding fingers extending to points adjacent the lower edge of the platen, and automatic means for opening and closing said fingers as they approach the limits of their movements.

16. Automatic sheet feeding mechanism for printing presses of the oscillating type comprising a vertical frame supported from the frame of the press in front of the platen, sheet feeding mechanism mounted on said frame, links connecting said feeding mechanism comprising coacting gripper fingers and to an operating shaft of the press, said links being detachable and said vertical frame having a hinge connection with said press frame at the side thereof, whereby said vertical frame and mechanism may be swung aside to permit access to the press.

17. In combination with a printing press of the oscillating platen type, sheet feeding mechanism, comprising a transverse shaft

5 journaled in front of the press, a pair of arms fixed adjacent the ends of said shaft positioned to move in vertical planes at the sides of the platen, sheet gripping and releasing devices supported from the upper ends of said arms and movable thereby in a curved path from a point adjacent the lower edge of the platen, when the latter is open, to a point in front of the press adjacent a 10 pile of sheets, automatic means for operating said gripping devices to cause them to take a sheet from the pile and deposit same on the platen at each operating cycle and return toward sheet receiving position before the platen closes including a crank on the operating shaft of the press, a link connecting said crank to one of said arms.

15 18. In combination with a printing press of the oscillating platen type, sheet feeding mechanism comprising sheet feeding mechanism including a plurality of pairs of horizontally aligned feeding fingers mounted to oscillate in vertical planes intersecting the platen, means operated in timed relation to the oscillation of the platen for oscillating said fingers in curved paths extending from points adjacent the lower edge of the platen, when the latter is open, to points in front of the press adjacent a pile of sheets, automatic means for actuating said fingers to cause them to close on a sheet presented thereto from said pile, and deposit same on said platen, and return toward sheet receiving position before the platen closes.

20 19. In combination with a printing press of the oscillating platen type, sheet feeding mechanism comprising two or more pairs of horizontally aligned feeding fingers, said fingers mounted to operate in vertical planes intersecting the platen, means actuated in timed relation to the operation of the platen for oscillating said feeding fingers in a curved path extending from the lower edge of the platen, when the latter is open, to an 25 elevated point in front of the press, whereby said fingers are removed from said platen when it closes and means for opening and closing said feeding fingers as they approach the limits of their movements towards and 30 away from the platen respectively.

25 20. In combination with a printing press of the oscillating platen type, sheet feeding mechanism comprising a pair of feeding fingers, means for mounting said fingers for bodily movement in vertical planes intersecting the platen, means actuated in timed relation to the oscillation of said platen for oscillating said fingers in superposed paths towards and from the face of the platen, the 35 path of said feeding fingers extending to a point adjacent the lower edge of the platen when said platen is opened, and automatic means for opening said grippers as they ap-

65 proach the lower position and closing them as they leave their upper position.

70 21. In combination with a printing press of the oscillating type, sheet feeding and delivering mechanism which feeds from and delivers to separate positions above and in front of the platen, comprising two or more pairs of horizontally aligned feeding fingers and two or more pairs of horizontally aligned delivery fingers, said fingers mounted to move in vertical planes intersecting the platen, means for reciprocating 75 said fingers bodily in timed relation to the oscillation of the press, said means operating to cause the feeding fingers to move over the face of the platen as the latter approaches the limit of its opening movement 80 to deposit a sheet thereon when in open position and operating to cause the delivery fingers to withdraw the printed sheet as the feeding fingers are moving over the platen, whereby said feeding and delivery fingers 85 are both above the platen and clear thereof when the impression is taken.

90 22. In combination with a printing press of the oscillating type sheet feeding and delivering mechanism which feeds from and delivers to separate positions above and in front of the platen, comprising two or more pairs of feeding fingers and two or more pairs of delivery fingers, means for reciprocating said fingers bodily in planes intersecting the platen and in superposed paths with the path of the feeding fingers above that of the delivery fingers, said means operating to cause the feeding fingers to move over the face of the platen as the latter 100 opens, to deposit a sheet thereon, and operating to cause the delivery fingers to withdraw the printed sheet under the sheet being deposited, whereby said feeding and delivery fingers are both above the platen 105 and clear thereof when the impression is taken.

110 23. In combination with a printing press of the oscillating type, sheet feeding and delivery mechanism which feeds from and delivers to separate positions above and in front of the platen, comprising feeding mechanisms operating to carry a sheet over the face of the platen and deposit same thereon when the platen is in open position and delivery mechanism operating to withdraw the printed sheet from the platen while the first sheet is being carried over the face of the platen, whereby said feeding and delivery mechanism is both above the platen 115 and clear thereof when the impression is taken.

120 In testimony whereof I hereunto affix my signature.

WALTER O. HALL.
